[57] CLAIM

The ornamental design for an armoire, as shown and described.

DESCRIPTION

FIG. 1 is a front perspective view of an armoire showing my new design;

FIG. 2 is a right side elevational view, the opposite side being a mirror image thereof;

FIG. 3 is a front elevational view thereof; and,

FIG. 4 is an enlarged perspective view of the pyramidal ornamentation thereof.

The top, bottom and rear views (not shown) form no part of the claimed design.

The broken line showing of environmental elements is for illustrative purposes only and forms no part of the claimed design.
